United States Patent Office

Des. 200,289
Patented Feb. 16, 1965

200,289

SINK

Max Schor, 518B 126th St., Rockaway Park, N.Y.

Filed Nov. 26, 1963, Ser. No. 77,576

Term of patent 7 years

(Cl. D4—2)

FIG. 1.

FIG. 2.

FIG. 2 is a top plan view thereof, and

FIG. 3 is a side elevational view thereof.

I claim:

The ornamental design for a sink, substantially as shown.
